G.M.T. haden INVENTOR
BY Victor J. Evans

WITNESS:

ATTORNEY

UNITED STATES PATENT OFFICE.

GERHARD MARTIN THADEN, OF READING, PENNSYLVANIA.

BELL.

Application filed May 15, 1926. Serial No. 109,352.

This invention relates to electric bells and its primary object is to provide an electric bell wherein the ringing mechanism therefor is confined within the walls of the bell and 5 base thereof respectively.

A further object is to provide an electric bell which is very simple in construction, composed of few parts and which may be manufactured and assembled at very little 10 cost.

This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying 20 drawings wherein like characters denote like or corresponding parts throughout the several views, and in which:

Figure 1 is a front elevation of the bell which forms the subject matter of the present invention.

Figure 2 is a side elevation thereof showing the same in applied position.

Figure 3 is a rear view.

Figure 4 is a sectional view taken on line 30 4—4 of Figure 1.

Figure 5 is a sectional view taken on line 5—5 of Figure 3.

Figure 6 is a sectional view taken on line 6—6 of Figure 3.

Figure 7 is a view of a stamped blank from which the armature of the bell is formed.

Figure 8 is a sectional view taken on the line 8—8 of Figure 3.

Referring to the drawings in detail the reference numeral 1 indicates the base for the bell 2 and extending from the flange 3 and secured upon diametrically opposite sides thereof is a substantially U-shaped bell 45 receiving bracket 4 having formed in its outer portion a threaded opening 5 to accommodate the screw bolt 6 which also passes through an opening formed in the bell for securing the same to the bracket in the manner as illustrated in Figure 4 of the drawings.

The bracket adjacent its outer portion is provided with a pair of spaced parallel ears 7 which are apertured to receive rounded projections formed upon opposite

sides and adjacent one end of the armature 55 arm 8 which is formed from the blank as shown in Figure 7 and bent substantially at right angles to its ends as indicated at 9 and 10. The end 10 has secured thereon the hammer 11 for the bell and the end 9 has 60 fixed thereto a weight 12 for a purpose which will be apparent.

The contact breaker arm is indicated by the reference numeral 13 and has one end insulated from and secured to the flange 3 65 of the base through the instrumentality of a terminal nut and bolt connection 14, while the opposite end is bent downwardly upon itself and receives the thumb screw 15 which is adjustably mounted therein and arranged 70 in the path of the free end of the strip 16 as shown in Figure 3, and said strip 16 has formed on its opposite end a lateral projection 17 which is secured to and insulated from the flange 3. 75

The electromagnet 18 is supported in the path of the upper weighted end of the armature 8 so that the core thereof will attract the armature for causing the operation thereof and which has formed integral therewith and cut therefrom as illustrated in Figure 7, the strip 19 which is arranged to engage the contact maker and breaker strip 16 for causing the same to cooperate with the screw bolt 15 to provide the intermittent 80 operation of the armature with the result 85 that the hammer thereof will strike the bell accordingly.

The electromagnet is supported by a link 19' which provides the ground connection 90 therefor and which is secured to the flange 3 by the terminal 20 as clearly shown in Figure 3 of the drawings. The terminals 14 and 20 are provided with the usual binding nuts for attaching the positive and negative 95 conduits from a suitable source of electric energy not shown.

The base 1 has detachably associated therewith a plate 21 which is formed with a key hole shaped slot 22 so that the bell can be 100 adequately supported from a nail or similar means 23 in the manner as best illustrated in Figure 4.

It is thought from the foregoing description that the advantages and novel features 105 of my invention will be readily apparent.

I desire it to be understood that I may make changes in the construction and in the

combination and arrangement of the several parts, provided that such changes fall within the scope of the appended claim.

What I claim is:

- 5 An electric bell of the character described comprising a base, a substantially U-shaped bracket secured thereto and rising therefrom, ears extending laterally from the bracket, an armature arm, rounded projections extending from the arm and being mounted for pivotal movement in the ears, a contact breaker arm having one end secured to and insulated from said base, a strip having one end secured to and insulated
- 10

from said base, a thumb nut threadedly secured in the contact breaker arm and adjustably arranged in the path of the strip, an electromagnet positioned so that it may attract the armature arm and being electrically connected with the strip, a strip cut from and integrally formed with the armature and arranged to actuate the strip first mentioned, a hammer secured to the armature arm, and a bell supported by said bracket in the path of the hammer.
